ROTARY FLUID DISPLACEMENT DEVICE

Ernest Alexander Cuny, New York, N. Y., assignor
to Cunward, Inc., Brooklyn, N. Y., a corpora-
tion of New York

Application July 20, 1935, Serial No. 32,371

12 Claims. (Cl. 103—127)

This invention relates to rotary fluid displacement devices.

It is desirable in compressing, delivering, or exhausting gases, in pumping liquids or in creating and maintaining vacuums, that a machine producing these results be of the positive-acting rotary type, simple and economical in construction with a minimum of moving parts, relatively free from friction, noise and wear, efficient in operation over a wide range of rotational speeds, and adapted to be direct-connected to a motor or other power drive source at the operating speed of the latter without the need of intermediate speed reduction means.

18 A considerable number of designs have been proposed for such rotary compressors, pumps and the like, but none have met with any degree of success due principally to the fact that when they are operated at even moderate speeds the friction developed causes excessive heating and for this reason they are usually required to be run in oil and are accordingly limited to those applications where the use of oil is not objectionable. The friction further causes excessive heating of 25 the compressed gas with resultant lowering of the efficiency of the machine due to drop in pressure of the compressed gas as its heat is dissipated after it is discharged from the machine. My invention overcomes these objections and obtains all the above mentioned desirable results.

30 A preferred embodiment of this invention comprises essentially two obliquely disposed shafts, one carrying a slotted conical disc and the other carrying a flat disc with integral blades perpendicularly disposed thereon and engaging said slots in the first mentioned disc, all being housed within a casing having a substantially spherical circumference with discharge ports therethrough, and sides shaped substantially similar to the 35 respective rotating discs and having suction ports therethrough, such that rotation of the elements within the casing causes alternate compression and expansion of the chambers defined by the oscillating blades, disc faces and casing, thereby resulting in suction and compression of the fluid therewithin. It further provides a second or additional stage of compression, obtained by extending the blade ends through the conic disc slots to positions proximate to a fixed conic 40 surface formed within the casing, this additional stage being operable in series, parallel or independently of the first mentioned stage.

45 The present invention is a continuation in part and comprises improvements upon the device disclosed in my co-pending application Serial

No. 19,191, filed May 1st, 1935 more particularly with respect to the blade disposition and the relative porting and baffling in devices of this type. It has for its object to provide a positive-acting rotary machine capable of use either as a gas 5 compressor or blower, liquid delivery or a vacuum pump, fluid meter or a like fluid displacement device which is simple and economical of construction and with a minimum number of readily accessible parts. It is a further object to provide a machine of the type described which will be relatively devoid of friction, noise and wearing of parts, and which will be efficient in operation over a relatively wide range of rotational speeds, and operable at the relatively high speeds 10 of the driving motor or other source of power to which it may preferably be direct-connected without the necessity of intermediate speed reduction means.

15 It is also an object to provide such a machine which requires relatively low starting torque when put into operation against a relatively high pressure on its discharge end or a comparatively low pressure on its suction end, and a machine which is flexible of arrangement and readily 20 adapted to multi-stage operation both in series relationship for increase in discharge or suction pressures and in parallel relationship for increases in discharge or suction volumes. It is a further object to provide a device of this 25 nature, which is self-priming when used as a liquid pump, and also to be capable of rotation in either direction.

30 It is also an object to provide a device of this nature having but two rotating elements within 35 a fixed casing and to further provide such a device having a second stage of compression between one of the rotating elements and the said fixed casing. It is also an object to provide such a device having a relatively high volumetric efficiency.

35 The present invention is an improvement over my copending application, above referred to, in that the device is improved and simplified by the provision of straight radial blades perpendicularly disposed upon the flat disc element which has an axis of comparatively lesser obliquity with that of the conoidal rotor, resulting in reduced offset and wear of the interconnecting universal 40 joint and lesser clearances and leakage between 45 the blades and slots. It also provides sealing ring construction separating lubrication from fluid spaces and reduces contact surfaces of rotating parts with the fixed casing thereby further 50 reducing friction and permitting higher rotational 55

speeds. It provides an improved location of suction ports such that centrifugal force assists in both suction and discharge of fluid. It further provides baffle portions attached to blades such that expanding compartments are prevented from taking compressed fluid from either the discharge line or compressing compartments.

Other objects and advantages of this invention will be apparent to one versed in the art in the course of the following description; all of which is understood to be within the scope of this invention and as more clearly enumerated in the subtended claims.

In the accompanying drawings, forming a part of this description, and in which like numerals are employed to designate like or similar parts throughout the same,

Fig. 1 is a plan, cross-sectional in part, of a fluid displacement machine embodying this invention;

Fig. 2 is a side elevation of the bladed element, partly cross-sectional, as taken along the lines 2-2 of Fig. 3;

Fig. 3 is an end elevation of the same;

Fig. 4 is an end elevation of the slotted element; and

Fig. 5 is a partly cross-sectional side view of the same as taken along the lines 5-5 of Fig. 4.

Referring to Fig. 1, the fluid displacement machine comprises essentially two rotating disc elements, 3 and 4, keyed or otherwise fixedly mounted upon their respective shafts 8 and 7 and adapted to be driven simultaneously and at the same speed within a fixed casing, comprising the two casing portions 13 and 14. Disc 4 is circular in shape, as more clearly shown in Fig. 3 and has a flat working surface 4F, exposed to the fluid which lies in a plane perpendicular to the axis Z-Z of the shaft 7 to which the disc is attached. Disc 3 is substantially conical in shape as shown in Fig. 5, and has a conical working surface 3F exposed to the fluid, and opposingly positioned with respect to the corresponding surface 4F of disc 4, which working surface 3F of disc 3 forms a frustum portion of a conical surface having an axis X-X corresponding to that of its attached shaft 8, the apex of the said cone coinciding with the said extended axis X-X of shaft 8 at a point O where the extended axis Z-Z of the obliquely disposed shaft 7 preferably intersects that of shaft 8. This point of axes intersection O preferably forms the normal center of rotation of the universal joint 7A-8A, or other flexible coupling means connecting the obliquely disposed shafts 7 and 8 and causing them to rotate in unison when either is driven from any suitable power source outside the casing, and which is too well known to those acquainted with the art to be further described.

Shaft 8 is journalled in a thrust type roller bearing 6 mounted in the casing 14, and shaft 7 is similarly journalled in a similar bearing 6 mounted in the opposite hub end of the casing 13.

The inner surface of the casing 14 designated by 14S exposed to the fluid, and more specifically that portion of the inner surface within which the periphery or edge of disc 3 is caused to rotate, forms a spherical surface the center of which is the center point O above referred to. The angle formed by the axes of the shafts 7 and 8, which is determined by the angularity of the conical disc 3, or vice versa, preferably causes the working surfaces 3F and 4F of both discs to be substantially parallel along one of their laterally extending radial center lines parallel and

coincident with the line Y-Y. In other words the sides of the space defined by the tangent portions of the disc working faces are substantially parallel at the horizontal plane through which the section of Fig. 1 was taken, as indicated by the dotted lines 3F and 4F and the dash line Y-Y, and this relationship is maintained at this point throughout the complete cycle of the rotating assembly. The hub portions of each casing are provided with annular sealing rings 13A and 14A which tend to prevent admixture of the bearing lubricant with the fluid being handled in the device.

Due also to the oblique relationship of the shafts 7 and 8, the oppositely extending portion of the working face 4F of the flat disc 4 is a comparatively greater distance from the opposed portion of the like face 3F of the conic disc 3 than it is at the 180 degree opposed portions, and forms a comparatively open angle instead of being parallel, resulting in the space 17 being considerably greater in area than the diametrically opposite space 16, and similarly the volumes of the spaces so represented likewise vary considerably.

The flat bladed disc 4 is provided with a cylindrical hub portion 4C and a spherical hub surface 4S which has point 28 as its center and is concentric with the similarly spherical surface 3S of disc 3 with which it is adapted to form a ball and socket joint.

The disc 4 is further provided with a plurality of blades 4A extending perpendicularly from its working face 4F and radially disposed with respect to center point 28 and the spherical portion of the hub 4S thereof, and equally spaced from each other. The outer or tip portion of these blades have spherical surfaces conforming to the cross-sectional outlines of the inner face 14S of the casing portion 14 having also point 28 for their center. The inner ends of these blades 4A terminate in the hollow spherical hub portion 4S, which is further adapted to form the ball portion of a ball and socket joint, of which the hub portion 3S of the conic disc forms the female or socket portion. This ball and socket joint 4S-3S forms a housing for the universal coupling 7A-8A which connects the obliquely opposed ends of shafts 7 and 8 and is adapted to prevent leakage of the compressed fluid into the housing, or to prevent the oil or grease with which the coupling 7A-8A may be lubricated from escaping into the fluid spaces indicated by 16 and 17, in addition to forming a contact surface over which the two discs oscillate with respect to each other. Both discs are also provided with hub portions 4C and 3C which are keyed in a suitable manner to their respective coupling halves and shafts 7 and 8 journalled within the hub portions of the casing 13-14 by bearings 6.

The conic disc 3 has a plurality of slots 3A extending in substantially radial directions from the spherical part of its hub 3S and through its entire working face portion from the said hub to its circumference or periphery. These slots or openings are positioned and dimensioned in width such that the blades 4A are adapted to reciprocate or oscillate therein with a minimum of friction and fluid leakage between the blade and slot surfaces which clearances are determined by the nature or characteristics of the particular fluid which is to be handled in the device. The variation in the angles at which the blades 4A intersect the surface 3F varies with the angle 75

ZOX, and at the small angle shown the blade excursion is greatly minimized. This reciprocatory movement of the blades within their respective slots is caused by the blades being rotated about an axis which is oblique to the rotational axis of the slots and results in the plane of a given blade face being intersected by the conic surface in a line which is of varying angularity with respect to the working surface 4F of the flat disc 4 depending upon the angular position of the said blade about its rotational axis Z—Z of the attached shaft 7. This angular reciprocation of a given blade within its slot completes one cycle, consisting of one opening and one closing movement of the enclosed chamber 16, during one complete revolution of the shafts 7 and 8. The closed, or compressed relationship of the disc faces represented by the space 16, and their open position indicated by 17, always remain in these relative positions, 180 degrees opposite to each other, and fixed with respect to the casing 13—14.

In the particular embodiment shown in Fig. 1, selected for illustrative purposes only, all rotational torque for turning the flat disc 4 is derived thereby from its attached shaft 7, driven through the universal coupling 7A—8A from shaft 8, there being no torque or other rotary forces imposed upon the blades of disc 16 by the slotted portion of the disc 15 in the embodiment shown. Shaft 8 may be driven from any power source external to the casing 14.

The ends of the casing housing the shafts 7 and 8 are sealed or made tight against leakage due to pressure within the casing by means of suitable stuffing box bonnets or end plates 9 and 10 which are additionally provided with suitable gaskets or spacing rings 21 and are attached to casing 13—14 by the usual tap bolts 11 engaging tapped holes in the hub portions of the casing sections 13 and 14. The casing halves 13 and 14 are bolted together by means of the tap bolts 12 passing through holes near the circumferences of the casing portions. The casing half 14 is preferably provided with a base portion of any known and suitable type for mounting upon a bed plate or other support (not shown).

The casing halves 13—14 are provided with suction ports 1A and discharge ports 2 for supplying and discharging fluids from each stage of the machine, that is, on either side of the rotating conic member 3. An improvement of the present invention lies in the provision of suction ports 1A through the sides of the casing halves and relatively nearer to the center of rotation of the compartments whereby centrifugal force due to high rotational speeds and weight of the fluid causes the latter to be carried to the outer portions of the compartments creating both a pressure decrease near the center and a pressure increase at the outer portions which assists in the suction and discharge flows respectively. Openings 1 are provided through the disc 4 at equal distances from the axis of rotation Z—Z such that they align with and permit intake of fluid through suction ports 1A in casing. Obviously the ports 1B will be plugged or otherwise closed when this feature of the device is utilized and the fluid drawn in through ports 1A and 1.

Baffles 5 are provided at the periphery of the disc 4 and extend circumferentially therewith for a distance which causes the discharge ports 2 in the casing to be intermittently sealed as each compartment enters and passes that position in its angular rotation where it would otherwise be

open to the discharge line while the adjacent compartment would also be open thereto. Similar baffles 5A are attached to the outer edges of the blades 4A by means of the fastenings 18. The width of the baffles 5 and 5A is slightly less than the clearances indicated by the narrowest widths of the compartments 16 and 17. The baffles serve to prevent expanding compartments, which have passed the angle of maximum compression, from taking in compressed fluid at a higher pressure from either the discharge line or the following compartment in which the pressure is about to reach its maximum.

The entire rotative assembly is journaled in the two roller bearings 6 and at no point other than these two bearings does it touch the casing or any other fixed part of the device. Minimum clearances are provided between all rotative and non-rotative parts, which clearances are determined substantially by the speed of rotation, the size and diameter of the device and the characteristics of the fluid to be compressed. The two rotative elements 3 and 4 comprising the rotative assembly, touch each other only at the spherical surfaces of the ball and socket joint 3S—4S and at the halves of the universal joint 7A—8A and the respective shafts 7 and 8 to which they are attached.

The bearings 6 are preferably pressure lubricated through fittings (not shown) positioned either in the end plates 9 and 10 or the adjacent hub portions of the casing. By providing a hollow portion in shaft 7 the universal joint 7A—8A and the ball and socket 3S—4S can be lubricated from the same source as the outer bearing 6.

In operation, we will first consider the compression of the fluid within the single stage portion of the device as defined by the discs 3 and 4 and the blades or partitioning members 4A. Suction and discharge pipes are suitably connected to the threaded ports 1A and 2 respectively, connection 1B being plugged, and the fluid is led into and fills the compartment 17. This space or compartment 17 formed between the casing surface 14S and the hub 4S, and between the angularly opposed working faces 3F and 4F of the respective discs is at this point in the position of maximum angularity of the disc faces and consequently the position of greatest volume of the compartment 17. As the shaft 8 is caused to rotate in either direction, carrying with it the discs 3 and 4 connected by the joint 7A—8A, the space 17 with its enclosed fluid is moved past a point where the port 1 in the disc 4 will pass beyond the inlet port 1A in the casing thereby preventing further passage of fluid into, or from, the compartment 17.

During the first half revolution the surface 3F moves from its position of maximum angularity with surface 4F, substantially equivalent to twice the angle at which the axes X—X and Z—Z intersect, or twice the angle ZOX, to the position diametrically opposite indicated by the space 16, where a radial line on 3F is parallel to the face 4F, and tangent at the line Y—Y. During this 180 degree angular rotation of the moving assembly, the volume of the space 17 has correspondingly decreased to that of space 16 and the fluid held therewithin between the same two blades or partitioning members has been compressed to a greater pressure than that at which it had entered through the port 1A. As the maximum compression is reached the foremost or leading blade passes beyond the discharge port 2 permitting the compressed fluid

to be forced into the discharge pipe, which when the point of greatest compression is passed, is sealed by the baffle 5.

As the rotation continues on the last half of its cycle or complete revolution the compartment gradually increases in volume while the baffle 5 continues to prevent blowback from the discharge, or the following chamber, permitting the residual fluid, which was not discharged, to expand or reduce in pressure until the port 1 again aligns with the suction port 1A at which point the pressure within the compartment will be less than the pressure prevailing within the suction pipe, thereby causing additional fluid to enter until the two pressures are substantially equal and the passing of the port 1 again cuts off the supply to the compartment at which time the cycle is started again.

In a similar manner the fluid entering the suction port 1A and the chamber 18 is compressed between the back or concave side of the disc 3 which also serves as a working face, and the conic surface 14C of the casing portion 14 which latter surface has Z—Z for its axis and is positioned and shaped to provide the proper clearance for the edges of the blades 4A. In this stage of compression, fluid is compressed between a rotating conic disc and a fixed conic disc, the blades not being fixed to either. A given point on any given blade surface will follow an oscillating or reciprocating path back and forth from the disc slot of its respective blade, or if near the middle of the blade surface it will pass through the slot twice during each revolution. As in the first described stage the fluid is similarly discharged from chamber 18 through the port 2.

When both of the above-mentioned stages are used, compression will be taking place on one side of a given portion of the disc 3 while expansion will be taking place on the opposite side. The suction and discharge ports 1A, 1B, and 2 have been shown in Fig. 1 within the horizontal plane which passes through both shaft axes, but they can obviously be located either above or below this plane in order to cut off the suction or discharge to suit any particular condition of operation or fluid characteristic for which the device may be designed.

When used as a gas compressor at high rotational speeds the clearances between the moving parts may be made sufficiently large to keep friction and heat within reasonable limits, and the leakage due to greater clearances is relatively small due to the comparatively high speed and large output, or delivery.

For use as a liquid pump the angularity of the conic disc 3 and obliquity of the shafts 7 and 8 is made comparatively small and the ports are preferably made oval shaped or longer in the direction of rotation and positioned such that the suction and discharge will take place throughout comparatively longer portions of the operating cycle, in order that expansion and compression will be reduced to a minimum. In a modification of this device for such use the conic disc 3 may preferably be replaced by a flat disc similarly slotted to receive the blades of the other flat disc.

As a gas compressor when it is desired to use but one of the two stages the other stage is preferably plugged at its ports and the gas therein will be alternately expanded and contracted with a minimum of expended energy, as the expansion in one compartment assists in the compres-

sion in the diametrically opposite compartment. Both stages may be operated in parallel in the same system or independently in different systems.

In a modification of my invention the fluid will first be compressed in the stage 18—19 and discharged directly into the suction port 1A, or 1B, of the second stage 16—17 for additional compression. The disc 3 is preferably shaped and positioned in this modification such that the volume of chamber 18 is substantially greater than that of chamber 17 in order that excessive expansion does not occur in delivering the gas thereto avoiding excessive pressure drop and maintaining a greater overall pressure differential between the suction pressure at port 1A of chamber 18 and the final discharge pressure at port 2 of chamber 16.

Obviously a machine comprising any number of such stages as described above could be built within the one casing, and the successive stages connected either in series or parallel depending upon whether greater pressures or volumes are desired.

My invention is not limited to the embodiment shown which has been selected for illustrative purposes only. It may be provided with 3 or more blades and the blade carrying member may be in the form of a conical disc similar to the slotted disc where greater ratios of compression and greater volumetric efficiency is desired. In other modifications both rotating discs may be either flat or plane surfaced, spherical or any spheroid of revolution in shape, or any combination of either of these shapes.

In another modification the universal joint may be dispensed with and the rotational torque transmitted from either disc through the blades engaging the disc slots. In still another modification the discs may be driven separately and at the same speeds from opposite sides of the casing.

While I have shown but one of the many possible modifications of my fluid displacement device, it will be understood that the shape and arrangements of the elements may be varied considerably to suit particular conditions, and it is intended that they all be considered as being within the scope and spirit of this invention.

What I claim is:

1. In a fluid displacement device, a rotatable element having radial fixed blades thereon, a casing having a chamber within which the said element is adapted to rotate, the said casing having a conic portion forming a part of said chamber and opposed to and having the same axis as the said rotatable element such that the edges of the said blades are adapted to rotate contiguously thereto, a rotatable conic element disposed intermediate the first said element and the said conic casing portion defining two compression stages, the said conic element having radial slots through which the said blades are adapted to reciprocate, the said conic element having a separate axis intersecting the first said axis, inlet and outlet ports in the casing between the said conic portion thereof and the said conic element, inlet ports through the casing and the first said element, and an outlet port between the first said element and the said conic element, and means adapted to rotate the said rotatable elements whereby fluid is caused to be drawn in through the said inlet ports and discharged through the said outlet ports of the respective stages.

2. In a fluid displacement device, a rotatable radially bladed element, a rotatable slotted ele-

ment adapted to receive the blades of the first said element within its slots, a casing having a spherical chamber within which the said elements are adapted to rotate on oblique axes, suction ports in the said casing and in the said bladed element, discharge ports in the said casing, baffles associated with said bladed element adapted to periodically close said discharge ports, and means for rotating the said elements such that compression of a fluid is caused between the said elements and the said casing and is adapted to be drawn through and discharged from the ports thereof.

3. In a fluid displacement device, a rotating element having radial blades fixedly mounted thereon, a rotating slotted element adapted to have the said blades reciprocate within the slots thereof, a casing having a spherical chamber within which the said elements are journalled and adapted to rotate on separate axes, the said axes intersecting within the chamber, inlet ports in the said casing and said bladed element, an outlet port in the said casing, baffles associated with the first said element adapted to periodically close the said outlet port, and flexible coupling means positioned at said axes intersection adapted to cause rotation to be imparted from one of the said elements to the other such that fluid supplied to the said inlet ports is caused to be discharged under increased pressure through the said outlet port.

4. In a fluid displacement device, a rotating radially bladed element having a hollow spherical hub, a rotating slotted element adapted to have the said blades reciprocate within the slots thereof, the said slotted element having a hollow spherical hub adapted to engage the hub of the first mentioned element, a casing forming a chamber within which the said elements are journalled and adapted to rotate on separate axes, the said axes intersecting within the chamber, inlet ports in the said bladed element and in the said casing, an outlet port in the said casing, the said spherical hubs of the said elements being adapted to form a ball and socket joint about which the said elements are adapted to oscillate, baffles associated with the said bladed element adapted to periodically close the outlet ports in the said casing, and flexible coupling means positioned at said axes intersection and within said ball and socket joint, whereby rotation may be transmitted from one of said elements to the other such that when either element is caused to rotate, fluid supplied to the said inlet port is caused to be discharged under increased pressure through the said outlet port.

5. In a fluid displacement device, a rotating disc element having blades radially disposed thereon, a rotating conic element having slots adapted to receive the said blades, a casing having a spherical chamber within which said elements are adapted to rotate, suction ports in the said casing and said bladed element, a discharge port in the said casing baffles associated with said bladed element and positioned to serve as closures of said discharge port at predetermined points in the rotational cycle, and means for imparting rotation to the said elements such that fluid enters one of the said ports and is discharged through another of said ports such that the said baffles prevent the undesired return of fluid from said discharge port into the device.

6. A fluid displacement device comprising two elements rotatable about separate intersecting axes, a casing within which said elements are

journalled for rotation, each of said elements having spherical hub portions adapted to form a ball and socket joint, one of the said elements carrying a plurality of blades extending radially from its hub portion, the other of said elements having slots radially disposed with respect to its hub portion, the said blades being adapted to reciprocate within the said slots upon rotation of the said elements, ports in the said casing, baffles associated with the peripheries of the blades adapted to periodically align with the said ports, and means for rotating the said elements.

7. In a fluid displacement device, elements rotatable about separate oblique axes, a casing within which said elements are journalled for rotation, each of said elements having spherical hub portions adapted to oscillatably engage each other, one of said elements having a plurality of partitioning members extending radially from its hub portion, another of said elements having openings radially disposed with respect to its hub portion, the said members being adapted to oscillate within the said openings upon rotation of the said elements, the said axes intersecting at the center of the said engaged hub portions, suction and discharge ports in the said casing, means associated with the said rotatable elements whereby suction and discharge are prevented during predetermined portions of the rotational cycle, and means to impart rotation to one of the said elements.

8. In a fluid displacement device, elements rotatable about separate oblique axes, a casing within which said elements are journalled for rotation, each of said elements having hollow spherical hub portions adapted to oscillatably engage each other, one of said elements having a plurality of blades extending radially from its hub portion, another of said elements having slots radially disposed with respect to its hub portion, the said blades being adapted to oscillate within the said slots upon rotation of the said elements, flexible coupling means connecting the said elements positioned within the said engaged hub portions, ports in the said casing, means associated with one of the said elements adapted to periodically close the said ports, and means to rotate one of the said elements.

9. In a fluid displacement device, a rotatable element having a plurality of blades radially disposed thereon, a casing having a chamber within which the said element is adapted to rotate, the said chamber being defined by an internal spherical portion of the said casing and a portion opposed to the said element, edges of the said blades being adapted to rotate in close proximity to the said casing portions, a second rotatable element having slots through which the said blades are adapted to reciprocate, the said second element being disposed within the said casing between the said opposed portion thereof and the first said element, the two said elements being adapted to rotate on separate intersecting axes, inlet and outlet ports in the casing adapted to form a compression stage between the two said elements, inlet ports in the first said element adapted to periodically align with the said inlet port in the casing, inlet and outlet ports in the casing adapted to form a second compression stage between the second said element and the said opposed casing portion, and means to rotate the said elements whereby fluid may be drawn in through the said inlet ports and discharged through the said outlet ports.

10. In a fluid displacement device, a casing having a chamber defined by spherical and opposed end surfaces, an element journalled for rotation in the said casing adjacent the first of 5 the said end surfaces, a second element having slots and journalled for rotation on an oblique axis within said casing intermediate the said end surfaces thereof, blades carried by the first said element and adapted to rotate in close proximity to the spherical and second end surfaces of 10 said casing chamber and to reciprocate within the said slots, an inlet and an outlet port in the said casing adapted to form a fluid compression stage between the said elements, inlet ports in 15 the first said element adapted to successively align with the said inlet port in the casing, inlet and outlet ports in the casing between the second said element and second said end surface adapted to form a second stage, and means to rotate 20 the said elements.
11. In a fluid displacement device, a casing having a chamber defined by spherical and opposed end surfaces, a rotatable element journalled for rotation in the said casing remote from 25 one of the said end surfaces, a second element having slots and journalled for rotation within said casing and being disposed between the first said element and the said remote end surface, the said remote end surface being generated about

the extended rotational axis of the first said element, partitioning means extending through the said slots and adapted to rotate with the said elements about the axis of the first said element and in relatively close relationship with the said spherical and remote end surfaces of said casing chamber, inlet and outlet ports in the said casing adapted to form fluid displacement chambers on both sides of the second said element, inlet ports in the first said element adapted to register with one of said casing inlet ports, and means to rotate the said elements. 5

12. A fluid displacement device comprising a rotatable element having radial blades, a second rotatable element having slots adapted to receive the said blades, a casing having a chamber within which the peripheral portions of the said elements are adapted to rotate in contiguous relationship, suction ports in the said casing and said bladed element, discharge ports in the said 15 casing, baffles associated with one of the said elements adapted to periodically close the said discharge ports and the suction port in the said casing whereby rotation of the said elements causes fluid intake through the suction ports and 20 discharge through the said discharge ports, the said baffles preventing undesired return of fluid from said discharge ports into the said chamber. 25

ERNEST A. CUNY.
